SWITCHING MECHANISM

Harry A. Douglas, Bronson, Mich.

Application February 6, 1932. Serial No. 591,260

14 Claims. (Cl. 200—8)

This invention relates to switching mechanism more particularly for automotive vehicles and electrical circuits associated therewith.

My invention is of particular utility in connection with switching mechanism which is assembled with the lower end of the steering column of an automotive vehicle, the switching mechanism being actuated by means located adjacent the upper end of the steering column.

10 Among other objects, the invention provides improved switching mechanism including an insulated contact keyed to rotate with a shaft and complementary contacts arranged in concentric arcs on one side of the axis of the shaft, associated with improved means for effecting a snap action of the contact.

The invention will be more fully explained by reference to the illustrative construction shown in the accompanying drawings, in which—

20 Figure 1 is a partial end view taken in the region of the steering wheel;

Figure 2 is a view partially in section, of an inclined steering column with my invention applied thereto;

25 Figure 3 is a section taken on the line 3—3 of Figure 5 and showing diagrammatically illustrative circuits associated therewith;

Figure 4 is a longitudinal section taken on the line 4—4 of Figure 5;

30 Figure 5 is a cross section taken on the line 5—5 of Figure 2 and somewhat enlarged.

Figure 6 is a perspective view of some of the complementary contacts in separated relation;

35 Figure 7 is a perspective view of another complementary contact;

Figure 8 is a plan view of the movable contact contemplated by my invention;

Figure 9 is a partial section taken on the line 9—9 of Figure 5; and

40 Figure 10 is a perspective view of the illustrative movable contact.

The switch actuating mechanism illustrated is inclusive of a rotatable hollow inclined shaft 1 which passes through a sleeve 2 (Figs. 4, 5) fixed

45 thereon by means of a clamping nut 3 which is screwed upon the tapered and longitudinally split threaded end 4 of the sleeve 2. A contact carrier here represented by the metallic clip 5 snugly embraces the sleeve 2. The sleeve embracing portion of the clip 5 is desirably formed

50 with tongues 6 (Fig. 9) which are struck inwardly to enter a slot 7 in the sleeve 2, thereby keying the clip to the sleeve. In this instance, the clip 5 has its sides 8 extended and overlapped as at

55 8a to form a radially extending bore 9 of square

cross section which snugly receives the insulating block 10 also of square cross section and itself formed with a radially extending bore 11 of square cross section. The bore 11 slidably receives a metallic contact shown generally at 12 (Figs. 8, 10). The contact 12 is therefore arcuately movable on rotation of the shaft 1, through the intermediation of the insulating block 10 and clip 5.

60 The movable contact 12 provides a current conducting bridge between complementary contacts carried by and within a casing 13 within which the clip 5 rotates. In accordance with my invention these complementary contacts are arranged in concentric arcs upon the upper side of the axis of the shaft 1. One of these complementary contacts is desirably produced in the form of an arcuate metallic plate 14, one end of which is mechanically and electrically connected to a metallic terminal post 15 which is carried

65 by a semi-cylindrical insulating wall member 16 fixed securely to and forming a part of the casing 13, as by being suitably clamped between the cup-shaped sections 17 and 18 of the casing, laterally disposed flanges 19 of the casing sections entering appropriately formed slots in the insulating wall member. The casing 13 is conveniently of generally cylindrical formation and the two sections of the casing between which the insulating wall member 16 is clamped may them-

70 selves be clamped together by ears 20 formed in a flange 21 on the casing section 17, for example, and clinched over a mating flange 22 formed on the casing section 18.

75 The arcuate plate 14 is slotted as at 23 to receive therethrough the contact 12 and in this instance the insulating block 10. The contact is shown provided with a hollow shank portion 24 of square cross section which is slidably received in the bore 11, the bore 11 and the hollow shank portion 24 together housing a coil spring 25 which presses the contact 12 radially of the shaft 1 and into engagement with complementary contacts

80 arcuately disposed on the insulating wall member 16 and in a plane perpendicular to the shaft 1 coincident with the plane of movement of the contact 12. The contact 12 is desirably provided with a somewhat dome-shaped head 26 which seats in cup-shaped contact portions 27 of metallic terminal members 28, 29, 30, 31, 32 and 33. At its end opposite the terminal 15 the plate 14 is mechanically and electrically connected to the metallic terminal post 34 carried by the insulating wall member 16. The terminal members 15 and 34 have reduced portions 35

85

90

95

100

105

110

which pass through the wall member 16, the ends of the reduced portions 35 being passed through appropriate apertures in holding flanges 36 formed at each end of the plate 14, the extremities of the reduced portions 35 being spun over the flanges 36. Thus the plate 14 is held rigidly in place upon the wall member 16 and within the casing 13 but insulated from the metallic walls of the casing. The terminal members 28 to 33 10 inclusive also have reduced portions 37 which pass through the wall member 16, the terminations of the reduced portions being spun over the inner surface of the wall member to secure the terminals thereto and also to provide the cup-shaped contact portions 27 already referred to.

The contact 12 is in this instance of forked formation having spring metal branches 38 and 39 each of which has two spaced apart contact surfaces comprising, as here shown, two spring 20 contact fingers 38a and 38b for the branch 38 and 39a, 39b for the branch 39. The spring fingers 38a and 39a may be integral and the spring fingers 38b and 39b may be integral, the fork members thus formed being secured to the 25 main portion of the contact 12 by having a reduced portion 40 of the shaft 24 pass therethrough at the junction of the fork and the head 26 being riveted over the fingers.

The contact branches 38 and 39 thus formed 30 project into engagement with the plate 14 by means of the spring fingers 38b and 39b and also by means of spring fingers 38a and 39a into engagement with other arcuate complementary contact plates disposed in the inner surface of 35 the wall member 16, as next described.

One of these other complementary contacts is here represented by the arcuate metallic plate 41 which is imbedded in the wall member 16 abreast of and upon one side of the terminal 40 members 29 to 33 inclusive. The plate 41 is extended as at 42 and through a perforation 43 in said extension the reduced portion 37 of the terminal member 29 passes and the cup-shaped portion 27 of the terminal member is clinched 45 over the extension 42, thus electrically connecting the plate 41 with the terminal member 29. The other complementary arcuate contact plate is represented by the metallic plate 44 which is imbedded in the insulating wall member abreast 50 of the terminal members 30, 31, 32 and 33 and upon the opposite side of these members from the plate 41. The plate 44 has a lateral extension 45 and through an aperture 46 in this extension is passed the reduced portion 37 of the 55 terminal member 30 and the cup-shaped portion 27 of the terminal being clinched thereover, thus electrically connecting the plate 44 with the terminal member 30. The plate 41 is disposed in a plane to be engaged by the contact finger 38a 60 of the contact 12 and the plate 44 is disposed in a plane to be engaged by the contact finger 39a of the contact 12 during the arcuate movement of the contact. Since the contact finger 65 38b travels in the same plane as the contact finger 38a and the former is in engagement with the plate 14 during the arcuate movement of the contact 12, the branch 38 comprising the fingers 38a and 38b provides a current conducting bridge between the plate 14 and the complementary contact plate 41. Similarly, the branch 39 which comprises the contact fingers 39a and 39b provides a current conducting bridge between the plate 14 and the plate 44. Also the 70 fingers 38b and 39b which are in engagement with the plate 14 provide a current conducting

bridge between that plate and one of the terminal members 28, 29, 30, 31, 32 or 33 with which the head 26 of the contact 12 is in engagement at the time. To enhance the natural resiliency of the spring fingers 38a and 38b and 39a and 39b, I have shown the coil springs 47 interposed between the fingers 38a and 38b and another such coil spring interposed between the fingers 39a and 39b, these springs being secured to tongues 48 struck out of the ends of the fingers. The coil springs desirably tend to separate the fingers of each pair and maintain them pressed against their respective complementary contact plates.

An insulated wire 49 (Fig. 3) electrically connects the terminal 15 with one side of the ground battery or other source of current 50. An insulated wire 51 connects the terminal 34 with the electromagnetic horn 52. Since the plate 14 is electrically connected with both the terminals 15 and 34, the plate 14 is in constant electrical connection with one side of the horn 50 and through the plate the horn 52 is also so connected. From the horn 52 an insulated wire 53 may pass through the hollow shaft 1 to an insulated contact button 54, housed centrally of the cup-shaped casing 55 surrounding the upper end of the shaft 1 and keyed to rotate the shaft as by the rivet 56 passing through the walls of the shaft and the inturned hub 57 of the casing 55. This hub 57 also supports a hollow insulating sleeve 58 which insulates the metallic contact button 54 in which the wire 53 terminates. To energize the horn a metallic cap 59 is superposed upon the casing 55 but is normally spaced from the contact button 54 by the action of the coil spring 60 housed by the casing. Movement of the cap 59 away from the casing 55 is limited by the closed end slots 61 in the casing and the studs 62 which pass through the cap 59 and into the slots 61. The cap is thus depressible axially of the casing against the action of the spring 60 and when so depressed engages the contact button 54 and a grounded circuit is completed to the horn through the casing 55, shaft 1, metal frame of the car and back to the other side of the battery. So constructed and arranged also rotation of the casing 55 rotates the shaft 1 to rotate the clip 5 carrying the movable contact 12.

When the clip 5 is in the position shown in Figure 5 the horn through the plate 14 is in electrical connection with the battery as just explained. The contact 12 is insulated from the plate 14 since the fingers 38b and 39b are engaged by insulating inserts 63 carried by the plate 14 flush with the contacting surface of the plate as by being received in the depressed portions 64 of the plate 14. This constitutes the "off" position of the switch. When, however, the clip 5 is rotated so that the head 26 of the contact 12 is in engagement with the terminal 28 a circuit is established through the grounded battery 50, plate 14, contact fingers 38b and 39b, terminal 28, insulated wire 65 and grounded parking lamps 66. At the same time a circuit is established through the grounded battery 50, plate 14, spring fingers 38b and 38a, plate 41, terminal 29, insulated wire 67, grounded rear lamp 68 and grounded instrument lamp 69. This constitutes one position of the switch for night use when the vehicle is not in motion.

When the clip 5 is rotated to have the head 26 of the contact 12 in engagement with the terminal 30 a circuit is established through the grounded battery 50, plate 14, fingers 39b and

39a, terminal 30, insulated wire 30a and to the ignition system of the vehicle indicated diagrammatically at 70. In this position of the contact 12 the spring contact finger 38a is out of engagement with the plate 41 since the plate at this point has its contact surface discontinued, a short section 76 of the plate 41 being covered by the insulating wall member 16. Consequently, the circuit through the tail lamp 68 and instrument lamp 69 is discontinued. While the spring finger 39a is in engagement with the plate 44 in this position of the switch, the plate 44 is merely a continuation of the terminal 30. This constitutes the day driving position of the switch.

15 When the clip 5 is again rotated to have the head 26 of the contact 12 in engagement with the terminal 31 a circuit is established through the grounded battery 50, wire 49, plate 14, contact fingers 38b and 39b, terminal 31, insulated wire 77 and through the grounded filaments 78 of the driving lamps 79. The filaments 78 may be the normal driving lights of the vehicle as by being located in the focus of the lamps 79. At the same time a circuit is established through 25 the grounded battery 50, wire 49, plate 14, contact fingers 39a and 39b, plate 44, terminal 30, wire 30a and ignition system 70. Also still another circuit is established through the grounded battery 50, plate 14, contact fingers 38b and 38a, 30 plate 41, wire 67 and through the rear lamp 68 and instrument lamp 69. This constitutes the normal night driving position of the switch.

When the clip 5 is again rotated to have the head 26 of the contact 12 in engagement with the terminal 32 a circuit is established through the grounded battery 50, plate 14, contact fingers 38b and 39b, terminal 32, insulated wire 80 and through the grounded filaments 81 of the driving lamps 79. The filaments 81 may be the intermediate driving lights of the vehicle as by being located above the focus of the lamps 79. At the same time another circuit is established through the grounded battery 50, plate 14, contact fingers 39b and 39a, plate 44, wire 30a and to the ignition system 70. Simultaneously also still another circuit is established through the grounded battery 50, plate 14, contact fingers 38b, 38a, plate 41, wire 67 through the rear lamp 68 and instrument lamp 69. This constitutes the 50 position of the switch when the vehicle is passing another car, for example, at night.

When again the clip 5 is rotated to have the head 26 on the contact 12 in engagement with the terminal 33 a circuit is established through the grounded battery 50, plate 14, spring fingers 38b and 39b, terminal 33 and to the grounded reading lamp 82 of the vehicle. At the same time another circuit is established through the battery 50, plate 14, contact fingers 39b and 39a, plate 44, wire 30c and to the ignition system 70. Simultaneously also still another circuit is established through the battery 50, plate 14, contact fingers 38b and 38a, plate 41, wire 67 through the rear lamp 68 and instrument lamp 69. This constitutes a selected position of the switch in which the parking and driving lights are extinguished.

It is very desirable that the clip 5 shall move into its respective positions by a pronounced snap action and I have provided a simple and improved structure to accomplish this result which is inclusive of a corrugated surface carried by the casing 13 and a spring pressed rider carried by the clip 5 to engage said surface. In this instance, the clip 5 is continued radially of the shaft 1 and upon the diametrically opposite side

of the shaft from the insulating block 10, the two sides 83 of the clip 5 thus continued being bent upon themselves to provide a bore 84 which, in this instance, is of square cross section and extends longitudinally of the shaft 1. The bore 84 may slidingly receive the hollow metal riders 85 at each end, the riders being pressed apart and outwardly of the bore 84 by a coil spring 86 housed by the bore 84 and the riders 85. Each of these riders desirably has a V-shaped nose 87 which rides over the corrugated surfaces 88 formed in the walls of each of the casing sections 17 and 18, these corrugated surfaces having hills 89 and valleys 90 oppositely arranged and also arranged so that when the riders 87 are in the valleys 90, the head of the contact 12 is centrally seated in one of the cup-shaped contact portions of the terminals 23 to 23 inclusive. Thus the contact must be moved from one terminal to the other against the action of the spring 86 and the hills 89. So arranged the spring 86 may be made of suitable capacity to effect the desired snap action more or less independently of the spring 25.

Rotation of the casing 13 during rotation of the clip 5 may be prevented by any suitable means. For example, as here shown, the casing 13 may be provided with a rigid finger 91 which is received between the forked end 92 of a bracket 93 suitably secured rigidly to the gear casing 94 100 carried by the stationary steering column 95.

The steering column may contain other rotatable shafts which do not enter into the present invention and therefore need not be described.

The rotatable casing 55 which rotates the shaft 1 may conveniently be provided with a pointer 96 and the different positions of this pointer corresponding to the respective positions of the contact 12 may be indicated upon a stationary dial plate 97 fixed below the casing 55.

Common subject-matter disclosed in this application and in my copending application, Serial No. 584,444, filed January 2, 1932, (Case 321) is broadly claimed in said copending application.

Obviously, the invention is not limited to the specific details of construction herein described for purposes of exemplification. Furthermore, it is not indispensable that all features of the invention be used conjointly as various combinations and sub-combinations may be advantageously employed.

Having described an embodiment of my invention, I claim:

1. In a switching mechanism, the combination with a rotatable shaft; of a clip projecting radially from the shaft and keyed to rotate with the shaft; a block of insulation secured between the sides of the clip; a contact carried by said block; a continuation of the clip extending radially on the opposite side of the shaft from the contact; an outwardly spring pressed rider on said continuation; and a corrugated member against which the rider bears, whereby the clip is rotated with a snap action.

2. The structure of claim 1 wherein there are two corrugated members and two riders disposed longitudinally of the shaft, the riders being pressed apart by a common spring against their respective corrugated members.

3. In a switching mechanism, the combination with a rotatable member; of an insulated contact keyed to rotate with the member; and complementary contacts arranged in concentric arcs on one side of the axis of the member in three different planes each perpendicular to said axis,

the contact simultaneously engaging the complementary contacts in all of the arcs to provide a current conducting bridge therebetween.

4. In a switching mechanism, the combination with a rotatable shaft; of an insulated contact member keyed to rotate with the shaft; and complementary contacts arranged in pairs in concentric arcs on one side of the axis of the shaft, the contacts of a pair being disposed longitudinally of the shaft and the contact member simultaneously engaging all of the complementary contacts to provide a plurality of conducting bridges therebetween.

5. The structure of claim 4 wherein the contact member is in the form of a fork, the branches of the fork each having spaced apart contact surfaces and wherein there are spring means in each branch pressing apart the contact surfaces of each fork.

6. The structure of claim 4 wherein the contact member is spring pressed radially of the shaft axis and is in the form of a fork having a central contact surface and four other contact surfaces provided by two branches of the fork, each branch having spaced apart contact surfaces and wherein there are spring means between the contact surfaces of each fork to press said surfaces apart.

7. In a switching mechanism, the combination with a rotatable shaft; of a clip projecting radially from the shaft and keyed to rotate with the shaft; a block of insulation secured between the sides of the clip; a contact member carried by said block; a continuation of the clip extending radially on the opposite side of the shaft axis from the contact member; a pair of riders carried by said continuation, said riders being spring pressed longitudinally of the shaft in opposite directions; and a casing receiving said mechanism,

the walls of the casing having a pair of oppositely disposed corrugated surfaces against which the spring pressed riders bear, whereby the clip is rotated with a snap action.

8. The structure of claim 7 wherein the riders are both received in a common bore in the clip continuation extending longitudinally of the shaft axis and wherein the riders are pressed apart by the same spring barrelled in said bore.

9. In a switching mechanism, the combination with a rotatable shaft; of a clip projecting radially from the shaft and keyed to rotate with the shaft; a block of insulation secured between the sides of the clip; a contact member carried by said block; complementary contacts arranged in concentric arcs on one side of the shaft axis, said contact member simultaneously engaging the complementary contacts in both arcs to provide a current conducting bridge therebetween; a continuation of the clip extending radially on the

opposite side of the shaft axis from the complementary contacts; a pair of riders carried by said continuation, said riders being spring pressed longitudinally of the shaft in opposite directions; and a casing receiving said mechanism, the walls of the casing having a pair of oppositely disposed corrugated surfaces against which the riders bear, whereby the contact member is moved with a snap action.

10. The structure of claim 9 wherein the riders are both received in a common bore in the clip continuation extending longitudinally of the shaft axis and wherein the riders are pressed apart by the same spring barrelled in said bore.

11. In a switching mechanism, the combination with a rotatable shaft; of a clip projecting radially from the shaft and keyed to rotate therewith; a block of insulation secured between the sides of the clip; a contact member carried by

said block; complementary contacts arranged in pairs in concentric arcs on one side of the axis of the shaft, the contacts of a pair being disposed longitudinally of the shaft and the contact member simultaneously engaging all of the complementary contacts to provide a plurality of current conducting bridges therebetween; a continuation of the clip extending radially on the opposite side of the shaft axis from the complementary contacts; a pair of riders carried by said continuation, said riders being spring pressed longitudinally of the shaft in opposite directions; and a casing receiving said mechanism, the complementary contacts being secured to the walls of the casing on one side of the shaft axis and the walls of the casing on the other side of the shaft axis having a pair of oppositely disposed corrugated surfaces against which the riders bear, whereby the contact member is moved with a snap action.

12. The structure of claim 11 wherein the contact member is in the form of a fork, the branches of the fork each having spaced apart contact surfaces and wherein there are spring means in each branch pressing apart the contact surfaces of each fork.

13. The structure of claim 11 wherein the contact member is spring pressed in the clip radially of the shaft axis and is in the form of a fork having a central contact surface and four other contact surfaces provided by two branches of the fork, each branch having spaced apart contact surfaces and wherein there are spring means between the contact surfaces of each fork to press the surfaces apart.

14. The structure of claim 3 wherein one of the planes contains a plurality of arcuately arranged complementary contacts of different radii engageable with the first mentioned contact.
